UNITED STATES PATENT OFFICE.

CHARLES A. JACKSON, OF ROCKFORD, ILLINOIS.

PEN OR PENCIL CLIP.

1,185,674.

Specification of Letters Patent. Patented June 6, 1916.

Application filed May 29, 1915. Serial No. 31,131.

To all whom it may concern:

Be it known that I, CHARLES A. JACKSON, a citizen of the United States, residing at Rockford, in the county of Winnebago and State of Illinois, have invented certain new and useful Improvements in Pen or Pencil Clips, of which the following is a specification.

In some of the clips heretofore produced, the clamping arm has been provided with a ball at its end to bear against the cloth of the pocket, and in others a sharp prong has been employed to engage the cloth. The ball tip lacks efficiency as a securing means, since the ball slides easily along the cloth so that the clip may be as readily slipped off as on. Clamping arms provided with sharp prongs are objectionable for the reason that the prongs are apt to catch in the cloth and fray or tear the same. Furthermore, such prongs are sometimes hard to disengage from the pocket.

The present invention contemplates certain improvements in pen or pencil clips with a view to providing a clip which may be easily slipped onto a pocket, which strongly resists accidental upward movement of the pen or pencil, which may be readily disengaged when it is desired to withdraw the pen or pencil and which will not tear or fray the cloth of the pocket. To this end the lower end of the clamping arm is provided with a pocket-engaging portion which extends upwardly from the inner side of the arm and lies at an acute angle to the axis of the pencil, and this portion is made quite broad and blunt so that while it serves as an effective grip to resist upward movement of the pencil, it will not tear or fray the cloth and will be readily disengageable therefrom. Means adapted to be grasped between the thumb and finger is also provided at the lower end of the arm for drawing the arm away from the cloth to disengage the same, this means being spaced a material distance from the pencil so that it may be readily grasped.

The invention also refers to a clip having a device thereon for receiving an initial, monogram, or other emblem.

In the accompanying drawings, Figures 1 and 2 are elevations at right angles to each other showing a fountain pen bearing a clip embodying the features of my invention. Fig. 3 is a plan view of the blank from which the clip is formed. Fig. 4 is an ele-

vational view with portions of the pen and the clip in section showing an alternative means for securing the clamping arm to the pen cap. Fig. 5 is a horizontal section in the plane of line 5—5 of Fig. 1. Fig. 6 is an enlarged section on line 6 of Fig. 2. Figs. 7 and 8 are elevations at right angles to each other illustrating an alternative construction.

A clip embodying my invention comprises an arm 10 and means at the upper end of said arm for attaching it to a pen or pencil. In the drawings, a fountain pen has been shown to illustrate the use of the clip, 11 being the body of the pen and 12 the cap thereof. The clip as a whole may consist of an integral piece, stamped from sheet metal and subsequently bent into form as will be presently explained.

The means for attaching the arm 10 to a pen or pencil may be in the form of a pair of clamping arms 13 which in effect constitute a split ring, or said means may comprise rivets or studs 14 adapted to pass through openings in the cap 12 and be riveted thereto as shown in Fig. 4.

On the extreme upper end of the arm is a holder 15 for a monogrammed member or emblem, said holder being bent down in front of the upper end of the arm 10. The holder comprises the apertured portion 16 which is connected by a narrow neck 17 with the upper end of the arm. The apertured part 16 is adapted to receive a member 18 upon which may be inscribed an initial, monogram or other emblem. Said member may be rabbeted at its periphery to provide a portion to fit snugly in the apertured holder and another portion of larger diameter to occupy the space between said holder and the arm, so that the member is held within its aperture. Obviously the holder 15 may be of various shapes or designs.

On the lower end of the arm 10 is provided means for engagement with a pocket to prevent accidental upward displacement of the clip, and also means to facilitate the disengagement of the arm when desired. In the form shown in Figs. 1 to 5, these means comprise an upwardly projecting foot 19 which is integral with or a continuation of the lower end of the arm, but is bent back upwardly to lie at an acute angle with respect to the axis of the pen or pencil. This foot is relatively long, a space being provided between its lower portion and the

- pencil to facilitate the introduction of the upper edge of the pocket between these two parts. The upper end of the foot 19 is quite broad and blunt, and while the acute angle 5 of the foot causes it to effect a fast engagement with the pocket, the broad end thereof prevents the foot from entering the mesh of the cloth so that all tendency of the foot to catch, tear or fray the cloth is eliminated. 10 If desired, a central notch 20 may be provided in the upper end of the finger to provide spaced apart fabric engaging members. On the lower end of the arm 10 adjacent to the finger 19 are two outwardly bent lugs 15 21, forming a finger grip adapted to be grasped between the thumb and finger to facilitate the bending outward of the arm for disengaging the finger from the pocket in withdrawing the pen or pencil therefrom. 20 By reason of the shape of the parts it will be seen that the lugs 21 are always spaced well away from the body of the pencil so that they may be easily grasped between the fingers. 25 In the form shown in Figs. 6 and 7 the fabric engaging foot is formed of two members 22 provided by slitting opposite sides of the arm to form upstanding projections. The lower end of the arm is continued in the 30 form of a curl 23 which provides a finger piece for drawing the arm away from the pencil. The members 22 and lower end of the arm extend at an acute angle with respect to the pencil in a manner similar to 35 the foot 19 so that a space at the lower end of the clip is provided for conveniently associating the same with the upper edge of the pocket. The two fingers 22 together provide spaced apart fabric engaging members having 40 a wide bearing against the pocket and both fingers are blunt or squared at their ends so that a good engagement of the mem-

bers with the pocket is effected without any danger of the fingers catching in the cloth and tearing or fraying the same.

45

I claim as my invention:

1. A pen or pencil clip comprising a body of flat resilient metal, and means for attaching one end thereof to a pen or pencil, the other end being free, the free end being provided with integral spaced apart fabric-engaging members having blunt edges to engage the surface of a fabric with a relatively wide bearing, said body having a finger grip bent from the body adjacent said fabric engaging member, whereby said members may be moved to disengage them from a fabric.

50

2. A pen or pencil clip comprising a body of flat resilient metal, and means for attaching one end thereof to a pen or pencil, the other end being free, the free end being provided with integral spaced apart fabric-engaging members having blunt edges to engage the surface of a fabric with a relatively wide bearing, said body having a side edges provided with outwardly bent lugs adjacent said fabric engaging members, to form a finger grip.

55

3. A pen or pencil clip comprising a body of flat resilient metal, and means for attaching one end thereof to a pen or pencil, the other end being bent to provide a relatively wide, blunted fabric engaging portion, said body having outwardly bent ears adjacent said fabric engaging portion to form a finger grip.

60

In testimony whereof, I hereunto set my hand in the presence of two witnesses.

CHARLES A. JACKSON.

In the presence of—

A. D. EARL,
IDALINE A. HESSE.
